UNITED STATES PATENT OFFICE.

JOSEPH L. MATTHEWS, OF HIGHLAND PARK, NEW JERSEY.

IMPLEMENT FOR EXERCISING.

Application filed December 29, 1923. Serial No. 683,280.

To all whom it may concern:

Be it known that I, JOSEPH L. MATTHEWS, a citizen of the United States, residing in Highland Park, in the State of New Jersey, **5** have invented certain new and useful Improvements in Implements for Exercising, of which the following is a specification, reference being had to the accompanying drawing, forming a part hereof.

10 This invention relates to an implement devised to insure exercise of a character entirely different from that derived from other mechanical means and is designed primarily for use by golfers. Understanding that the invention is not to be limited in respect to the use to which it is put it will, nevertheless, be described herein for convenience as embodied in a device which will insure to golfers a simulation of conditions surrounding the swing of a golf club and, according to, insure a maintenance of such muscular activity as is requisite for satisfactory play.

A golf club of given weight and length propelled by the energy impressed thereon by a particular player and swung through an arc whose center is theoretically the left shoulder of the player and whose radius is the distance of the center of mass of the club from the left shoulder has a given amount of energy at the instant the head engages the ball. To produce a swing in proper form it is necessary that many muscles be delicately co-ordinated and responsive, a condition which can be obtained and maintained only by constant practice. The average golfer finds it impossible because of limitations on his time to devote such practice to the game as will insure the best results and he finds, particularly in winter, that entire lack of practice and exercise permits his muscles, through disuse, to grow unresponsive and undependable. It becomes desirable, therefore, to provide an exercising implement which will not only satisfy the demands of non-golfers for a beneficial and interesting exercise but will particularly supply for golfers that need for constant practice and the regular use of the golfing muscles. To satisfy this demand the improved device comprises an abbreviated staff of such weight and length as will best suit the user. Since the exerciser will ordinarily be used indoors and, more particularly, within the narrow confines of an ordinary household room, it is proposed to make its length such as to obtain

a freedom for full swing without the jeopardy of contact with other objects in and about the room. The staff as thus provided may for convenience be tapered slightly and formed with a suitable surface to facilitate gripping. When designed particularly for use by golfers the staff will, in addition, be weighted and its center of mass so disposed as to insure for a particular player the creation of approximately the same energy, taking into account the shorter length, as is created by that player when swinging a standard golf club of typical weight and length. **60** **65** **70**

The invention will be described with greater particularity hereinafter with reference to the preferred embodiment shown in the drawings, wherein:

Figure 1 is a schematic view showing one of the improved implements as grasped by the two hands of the user and the factors taken into account in creating the same conditions surrounding its use as are found when the user swings a club of conventional form. **75** **80**

Figure 2 is a view in perspective of the preferred form of exerciser.

As pointed out hereinbefore, it is believed that the exerciser will make its widest appeal to golfers because of the fact that with it they are able to simulate conditions of swinging a golf club and it is for this reason that such an embodiment is illustrated in the drawings and will be described in some detail herein but it is to be understood that a non-golfer may obtain an interesting and beneficial exercise by its use. **85** **90**

In Figure 1 of the drawings there is indicated what is called the center of motion about which it may be supposed that the arms swing with a standard golf club. Such a point, theoretically, is located at the left shoulder of the player. A standard golf club *a* when grasped by the hands of the player is swung about this center of motion and the energy of its impact with the ball for a particular player is dependent upon the distance *R* of the center of gravity of the club from the center of motion and upon the weight of the club. In creating a given energy at the instant of impact a player has brought into use many muscles which properly co-ordinated insure effective timing of the swing and maximum distance and accuracy. By means of the improved device illustrated generally at **95** **100** **105** **110**

b it is proposed to place in the hands of a golfer an implement which may be used in quarters of limited space and yet create for him the precise conditions attendant upon the swinging of a standard club. In thus simulating conditions the implement b is preferably so designed as to bring its center of gravity b' in proximity to the hands of the user but below the grip. 10 This may best be done by forming the staff b hollow as indicated at b² for a substantial distance and weighting the end as by means of the mass b³ which itself may assume any form without departing from the invention. 15 It has been found, however, that a generally spheroidal form has the least tendency to distract the attention of the user. Having thus located the center b' of gravity of the device when it is held in the hands of the 20 user it is evident that this center of gravity will swing about the center of motion on a radius r. For a given user the weight required to simulate conditions found in swinging a club such as a varies inversely 25 as the square of the radii, that is, the theoretically correct weight of the imple-

$$W \\ \text{ment} = \frac{W}{\left(\frac{r}{R}\right)^2} \text{ where } W \text{ is the weight of a}$$

30 standard golf club.

It is to be understood that this mathematical relation may be somewhat theoretical and that different weights may be more acceptable to different users but it has been 35 sought herein merely to illustrate the approximation of conditions which is sought by the invention. That the conditions are substantially simulated has been proven out by actually determining the energy at impact in foot pounds by which a given flight 40 of ball is secured and by simple proportion determining the angular velocity of the shorter exerciser and its necessary weight to give, at such velocity the same energy 45 when manipulated by the same user.

Considering now some of the details of the device which are important in contributing to its proper use it will be noticed that the part which is to be grasped may be 50 tapered and the surface formed with con-

venient grip as through serrations b⁴. The grip thus afforded is substantially like that of a standard club. When properly grasped the hands may be given the correct position along the staff and an "address" made with the proper stance to the end that the swing with the implement in hand may wholly simulate the conditions surrounding the swing of a club and the same energy be created thereby. The limbs, wrists and body are all employed in precisely the way conducive to a proper golf swing and are stressed to the same extent. All of the muscles both major and minor which contribute to a satisfactory swing for distance and accuracy are brought into play by the improved exerciser and thereby maintained in a responsive condition at all times. The danger attendant upon the swinging of a golf club within the confines of an ordinary 70 household room are eliminated and the user is enabled to take full free swings without reservation but with the same effect as induced in the swinging of a golf club.

It is to be understood that the invention 75 is not to be limited in respect to size, shape or weight since it may be varied within wide limits to suit conditions of strength, height and other physical characteristics of different persons.

What I claim is:

1. An exercising implement for use in simulating the conditions of a golf swing within a space of limited confines comprising a short staff having an abbreviated grip for the hands and a predetermined weight and a center of gravity located at a predetermined point.

2. An implement for use in simulating the conditions of a golf swing comprising a short staff having a grip for the hands and a weight which is substantially equal to the weight of a standard golf club divided by the square of the radius of motion of the center of gravity of the device divided by the radius of motion of the center of gravity of a standard club.

This specification signed this 27th day of December, A. D. 1923.

JOSEPH L. MATTHEWS.
